GRILLE GUARD FOR MOTOR VEHICLES

Filed May 7, 1947

FIG. 1.

FIG. 2.

INVENTOR:
LEO BUSTIN.

BY: Julian J. Wittal

HIS ATTORNEY.

UNITED STATES PATENT OFFICE

152,058

DESIGN FOR A GRILLE GUARD FOR MOTOR VEHICLES

Leo Bustin, New York, N. Y.

Application May 7, 1947, Serial No. 138,886

Term of patent 3½ years

(Cl. D14—6)

To all whom it may concern:

Be it known that I, Leo Bustin, a citizen of the United States, residing at New York city, in the county of New York and State of New York, have invented a new, original, and ornamental Design for Grille Guard for Motor Vehicles, of which the following is a specification, reference being had to the accompanying drawings, forming a part thereof.

In the drawing:

Fig. 1 is a front view of a grille guard for motor vehicles, showing my new design;

Fig. 2 is a plan or top view thereof.

I claim:

The ornamental design for a grille guard for motor vehicles, as shown.

LEO BUSTIN.
